UNITED STATES PATENT OFFICE.

JOHN FRANCIS BRICE, OF BENSalem TOWNSHIP, BUCKS COUNTY, PENNSYLVANIA.

PLANE FOR AIRCRAFT.

1,406,923.

Specification of Letters Patent. Patented Feb. 14, 1922.

Application filed April 6, 1921. Serial No. 458,926.

To all whom it may concern:

Be it known that I, JOHN FRANCIS BRICE, a citizen of the United States, and resident of the township of Bensalem, in the county 5 of Bucks and State of Pennsylvania, have invented a new and Improved Plane for Aircraft, of which the following is a full, clear, and exact description.

My invention relates to a flying machine, 10 and aims to provide certain new and useful improvements in connection with aerofoils.

In connection with aircraft utilizing lifting surfaces commonly termed "aerofoils" it is a well appreciated fact that the maximum 15 of theoretical efficiency which a lifting surface should be capable of exerting is not produced thereby.

Although this defect is particularly noticeable in connection with the wings, ailerons and lifting planes of an airplane, it is also to be found in those surfaces acting as 20 lifting planes, which are associated with dirigibles.

Also the blades of the propeller or screw 25 utilized in all types of flying machines have failed to produce the amount of traction or push of which they are theoretically capable.

With regard to the supporting surfaces, etc., numerous designers have attempted to 30 increase the efficiency of the lifting surfaces by providing structure permitting of the camber of these surfaces being varied so that the wings, etc., might have their bodies disposed in certain planes upon the machine 35 "taking off", and subsequent to this "taking off" allow the camber to be varied to reduce head resistance, although not sacrificing the lifting qualities of the supporting surface.

Although certain improved results have 40 been noticeable in utilizing this expedient, the machine as a whole, has fallen far short of its theoretical possibilities, and perhaps the most efficient structure of this type suggested has been that in which the aerofoils 45 consist of a plurality of units co-operating with each other, to provide one element, the operation of which unit may be varied by the movement of the individual elements.

With this in view I have constructed cer- 50 tain improvements in connection with flying machines, and more particularly those portions of the same which are commonly termed aerofoils, which class includes lifting surfaces, ailerons, elevating planes, air screws, etc., and by means of which the efficiency 55 of any unit falling within this class

will be greatly increased, in that primarily, the head resistance offered by the leading edge of each of the units specified will not be increased in ratio to the speed of the air 60 currents to the extent that this now occurs.

Thus a flying machine utilizing my improved construction will be capable of a far greater amount of speed with the same engine power, without in the slightest effect- 65 ing its lifting qualities.

A further object of my invention is the construction of a device of the character stated in which a given area will exert a far greater amount of "lift" than has hereto- 70 before been possible.

Still other objects of my invention are the provision of ailerons of such a construction that a machine equipped with the same may be more readily responsive and more nearly 75 approach the theoretical possibilities of which it is capable.

Reference is had to the annexed specification taken in connection with the drawings, which latter present practical embodiments 80 of my invention, and in which:

Figure 1 is a side edge view showing one type of aileron.

Figure 2 is a similar view embodying my improved construction as applied to a sec- 85 ond type of aileron, and

Figure 3 is a sectional view of still a dif- 90 ferent form of surface.

It is to be noted that each of these views illustrates my invention diagrammatically, 90 but it will be noted that the same incorpo- 95 rates the principles involved.

Reference being had to Figure 1 it will be noted that an aerofoil is shown, which aero- 100 foil as in the initial construction of units of this character, presents a substantially flat upper surface 5, but contrary to the conven- tional construction, has its lower surface 6 bulged or convex. Also in Figure 2, it will be noted that the lower surface of the aero- 105 foils is similarly formed, but the upper sur- face 7 in this instance is hollowed or con- cave.

Finally with respect to the structure illus- 110 trated in Figure 3, it will be noted that a lifting element is provided, which includes a plurality of separate aerofoils 8, having their lower surface curved, and having spaces 9 existing between the aerofoils, so that the passage of air currents is permitted 115 downwardly between the aerofoils.

I believe that aerofoils constructed in ac-

cordance with my invention present all of the advantages set forth in the preamble of this specification, and I attribute this improved operation to the curvature presented 5 by the underside of the aerofoils, although in certain instances, the beneficial action of the same may be enhanced by adapting the structure suggested in the forms illustrated.

Obviously numerous modifications of 10 structure might readily be resorted to with-

out in the least departing from the spirit of my invention, which I claim as:

A device of the class described including a plurality of separate aerofoils arranged in tandem, and secured together to provide a 15 single element, said element presenting openings between said aerofoils, each of said aerofoils presenting a convex under surface, and a non-convex upper surface.

JOHN FRANCIS BRICE.
